(57) **CLAIM**

The ornamental design for a storage case for portable tool, as shown and described.

DESCRIPTION

FIG. 1 is a front view of a storage case for portable tool showing my new design;

FIG. 2 is a rear view thereof;

FIG. 3 is a left side view thereof;

FIG. 4 is a right side view thereof;

FIG. 5 is a top plan view thereof;

FIG. 6 is a bottom view thereof; and,

FIG. 7 is a top, front, right, perspective view thereof.

The broken lines in FIG. 2 illustrate unclaimed portions of the storage case for portable tool and form no part of the claimed design.
